tion, Los Angeles, Calif., a corporation of Cali-
fornia

Application May 24, 1948, Serial No. 146,554

Term of patent 14 years

(Cl. D21—3)

To all whom it may concern:

Be it known that I, James C. Bennett, a citizen of the United States and a resident of Inglewood, California, have invented a new, original, and ornamental Design for a Cord Guide for Venetian Blind Mounting Brackets, of which the following is a specification, reference being had to the accompanying drawing, forming part thereof.

Referring to the drawing:

Figure 1 is a perspective view, showing the front and side of a cord guide for Venetian blind mounting brackets, incorporating my new design;

Figure 2 is a perspective view showing the same side and the back of the guide and control member;

Figure 3 is a front elevation of the guide and operator;

Figures 4 and 5 are elevations of opposite sides respectively thereof;

Figure 6 is a rear elevation thereof;
Figure 7 is a top plan view thereof; and
Figure 8 is a bottom plan view thereof.

I claim:

The ornamental design for a cord guide for Venetian blind mounting brackets, as shown.

JAMES C. BENNETT.
